UNITED STATES PATENT OFFICE.

WILLY DUMKE, OF CHICAGO, ILLINOIS, ASSIGNOR TO HIGH FREQUENCY LABORATORIES, OF CHICAGO, ILLINOIS, A CORPORATION OF ILLINOIS.

TRANSFORMER AND MOUNTING THEREFOR.

Application filed April 7, 1927. Serial No. 181,690.

This invention relates to improvements in 5 transformers and mountings therefor, and more especially to such a transformer and mounting of the type frequently employed in connection with radio apparatus, for example, radio receiving sets. The invention is particularly applicable to transformers of the radio frequency type.

My improved transformer is neat, simple, 10 efficient, and pleasing in design and appearance.

One of the features of my invention is to 15 provide a mounting for the transformer with improved terminals adapting it for quick and easy attachment to various radio units, for example, directly to the terminals of tube sockets, or directly to wires, either on the front or back of a panel. These features make the transformer practically universally adaptable for use in all locations 20 and under various circumstances.

Other features and advantages of my invention will appear more fully as I proceed with my specification.

In that form of device embodying the 25 features of my invention, shown in the accompanying drawings, Fig. 1 is a view taken as indicated by the line 1 of Fig. 2, Fig. 2 is a top plan view showing a portion of the 30 cover removed, Fig. 3 is a vertical sectional view taken through one of the terminals, showing the transformer mounted on the back of a panel and adapted for connection to a wire on the front of the panel, and Fig. 4 is a top plan view of a portion of 35 the transformer, showing the same attached directly to the terminals of two tube sockets.

As shown in the drawings, the device comprises a substantially rectangular base plate 40 10, made of any suitable insulating material, for example, bakelite, hard rubber, fibre, and the like, provided with a hole 11 in each corner. These holes on the rear side are somewhat enlarged or countersunk, 45 as indicated by 11^a. There is also an additional hole 12 at each end of the plate in the center to be used in mounting the plate.

The primary and secondary coils of the 50 transformer as indicated by 13, 13^a respectively, may be mounted upon the base plate 10 in any suitable manner. For example, these coils may be wound about a wooden core 14 attached to the base plate 10 by means of the screws 15. The core 14 may

be pulled down to hold the condenser 17 in 55 place, the screws 15 passing through tubes 16 inside of the condenser. Obviously, any other suitable means may be employed for supporting the coils on the plate 10. The particular manner of supporting the coils 60 forms no part of the present invention except as the same may be claimed in combination with other features.

The terminals of the coils are connected 65 to flat sheet-metal terminal strips 18, one mounted at each corner of the plate 10 by means of the hollow rivets 19 in the holes 11. The usual connections of the terminals of the coils are made. For example, as here 70 shown the terminals of the primary coil are connected to the terminal strips indicated by P and B and those of the secondary coil are connected to the terminal strips indicated by G and F; such markings being the conventional markings on transformers of 75 this type. The end of each of the terminal strips 18 is provided with a hole 18^a to assist in attaching a wire thereto. It will be seen that since the terminal strips 18 project beyond the edge of the base 10, they may be 80 directly connected to the terminals of two adjacent tube sockets. Thus connected, they are shown in Fig. 4 where 20, 20 indicate two tube sockets. It will be seen that the terminal strips P and G of the transformer 85 are connected directly to two of the terminals of the adjacent tube sockets without the use of any connecting wires, thus permitting the connections to be made without 90 any soldering.

In Fig. 3 a portion of the transformer is shown as mounted on the back of a panel 21. When thus mounted, a terminal of the transformer may be connected to a wire on the front of the panel in the following manner. 95 The panel 21 is provided with a hole 22 adjacent the corresponding hole 11 of the transformer, and a small metal projection 23 may be fastened in the hole 11 by means of the bolt 24. A wire 25 on the front of the 100 panel may be connected to the end of the part 23 projecting through the hole 22 in the panel.

It will be seen, that, in general, each terminal of the transformer is provided with 105 a strip 18 to which a wire may be soldered; and each such terminal is also in contact with a hollow rivet 19 lying in the hole 11.

There is thus provided a hole for each terminal in which a bolt may be fastened to attach any wire or other part directly to the terminal by means of such bolt. The back of the hole 11 being countersunk, as indicated by 11^a, prevents the rear end of the rivet 19 from coming in contact with the panel 21 or other member upon which the base 10 may rest.

26 indicates a suitable cover for the coils and condenser adapted to be suitably spaced on the plate 10 by the lugs 27. The cover may be fastened in place in any suitable manner as, for example, by means of the small tacks or drive screws 28, extending through the lower edge of the cover 26 and adapted to enter the lugs 29 formed on the base plate 10.

While I have shown and described certain embodiments of my invention, it is to be understood that it is capable of many modifications. Changes, therefore, in the construction and arrangement may be made without departing from the spirit and scope 25 of the invention as disclosed in the appended claims, in which it is my intention to claim all novelty inherent in my invention as broadly as possible in view of the prior art.

What I claim as new, and desire to secure 30 by Letters Patent, is:

1. A transformer comprising; a base plate of insulating material with four holes there-through; a pair of coils; means on the base plate for supporting the coils thereon; a cover for the coils; means on the base plate for supporting the cover; four terminal pieces having their inner ends connected to the coil terminals and the outer ends projecting beyond the base plate; and means 40 for attaching the terminal pieces to the base plate, said means including hollow rivets extending through the holes in the base plate.

2. A transformer comprising; a base plate of insulating material with four holes there-through; a pair of coils; means on the base plate for supporting the coils thereon; a cover for the coils; means on the base plate for supporting the cover; four terminal pieces having their inner ends connected to the coil terminals; and means for attaching the terminal pieces to the base plate; said means including hollow rivets extending through the holes in the base plate.

3. A transformer comprising; a base plate of insulating material with four holes there-through; a pair of coils; means on the base plate for supporting the coils thereon; a cover for the coils; means on the base plate for supporting the cover; four terminal pieces having their inner ends connected to the coil terminals and the outer ends pro-

jecting beyond the base plate; and means for attaching the terminal pieces to the base plate, said means including hollow rivets 65 extending through the holes in the base plate, the rear ends of the rivets being countersunk in the base plate.

4. A transformer comprising; a base plate of insulating material with four holes there-through; a pair of coils; means on the base plate for supporting the coils thereon; a cover for the coils; means on the base plate for supporting the cover; four terminal pieces having their inner ends connected to 70 the coil terminals, and means for attaching the terminal pieces to the base plate, said means including hollow rivets extending through the holes in the base plate, the rear ends of the rivets being countersunk in the 80 base plate.

5. A transformer comprising; a base plate of insulating material with four holes there-through; a pair of coils; means on the base plate for supporting the coils thereon; a 85 cover for the coils; means on the base plate for supporting the cover; four flat sheet-metal terminal strips having their inner ends connected to the coil terminals and the outer 90 ends projecting beyond the base plate; and means for attaching the terminal strips to the base plate, said means including hollow rivets extending through the holes in the 95 base plate.

6. A transformer comprising; a base plate 95 of insulating material with four holes there-through at the corners; a pair of coils; means on the base plate for supporting the coils thereon; a cover for the coils; means on the base plate for supporting the cover; 100 four terminal pieces having their inner ends connected to the coil terminals and the outer ends projecting beyond the base plate; and means for attaching the terminal pieces to the base plate, said means including hollow 105 rivets extending through the holes in the base plate.

7. A transformer comprising; a base plate of insulating material with four holes there-through; a pair of coils; means on the base 110 plate for supporting the coils thereon; a cover for the coils; means on the base plate for supporting the cover; four terminal pieces having their inner ends under the cover and connected to the coil terminals and 115 the outer ends projecting beyond the base plate; and means for attaching the terminal pieces to the base plate, said means including hollow rivets extending through the 120 holes in the base plate.

In witness whereof, I have hereunto set my hand and seal this 5th day of April, A. D. 1927.

WILLY DUMKE. [L.S.]
